THERMIONIC-VALVE SYSTEM

Maurice K. Taylor, Hollinwood, and Frederic C. Williams, Manchester, England, assignors to Ferranti Limited, Hollinwood, England, a corporation of Great Britain

Application July 22, 1947, Serial No. 762,641
In Great Britain November 5, 1945

Section 1, Public Law 690, August 8, 1946
Patent expires November 5, 1965

12 Claims. (Cl. 250—36)

1 This invention relates to thermionic-valve systems. More particularly the invention relates to improvements in thermionic-valve oscillatory systems of the type disclosed and claimed in the co-pending application of Maurice K. Taylor et al., Serial No. 766,392, filed August 5, 1947, entitled "Control arrangement for thermionic valve systems," and assigned to the same assignee as the present application, wherein it is possible to provide either for the cyclic operation of each of such systems singly in predetermined order or for the substantially uninterrupted operation of only a specific one of them.

The expression "substantially uninterrupted operation" used above and hereinafter is intended to mean that the specific system operates continuously except for a short interruption at the end of each operating cycle of the control arrangement.

In the specification of the above-identified co-pending patent application, there is described a thermionic-valve system comprising two signal-modifying means together with a switching system which either allows the two means to operate alternately or allows only a specific one of them to operate. Operation or nonoperation of a signal-modifying means is determined by the connection or disconnection of the high-tension supply to the receiving and transmitting valves included in the signal-modifying means.

Certain difficulties arise during the period of change-over from one signal-modifying means to another, that is to say, when the high-tension supply is disconnected from one means and connected to the other.

The first difficulty arises from the fact that the receiving valve and transmitting valve of each means are each provided with an automatic grid-biasing arrangement comprising a resistance in parallel with a condenser in the cathode lead. Consequently when, after such a means has been operating, the high-tension supply to it is disconnected due to movement of the switch, the condenser forming part of the grid-biasing means discharges and the potential of the cathode of the valve becomes nearly equal to earth potential. When the high-tension supply to this means is switched on again after a period during which the other signal-modifying means has been operating, the negative bias potential applied to the receiving valve and the transmitting valve in the first-mentioned means is small since their cathodes are nearly at earth potential, and it is usually so small as to allow self-oscillation in each control-grid cathode circuit to occur, thereby

2 causing unwanted transmission. This state of affairs continues until the cathode potentials rise to their operating values.

A second difficulty arises because a connection is made to the control grid of the transmitting valve in each means from the anode of an amplifier valve which is common to both means. When a signal pulse is received by an operating signal-modifying means, the potential of the anode of the common amplifier valve rises. Hence not only does the potential of the control grid of the transmitting valve in the operating means rise positively, but so does the potential of the control grid of the transmitting valve in the non-operating means. In the case of this latter valve, its anode potential is zero, its control-grid potential is positive and its cathode potential is nearly that of earth. Consequently, the control grid and cathode of this transmitting valve may operate as a diode valve, the control grid taking current. It will be seen that a transmitting valve in a non-operating means may thus add an extra load to the common amplifier valve, thereby reducing the driving power applied to the transmitting valve in the operating means. This would cause a reduction in the amplitude of the pulse transmitted from the operating means. Furthermore the width of the pulse may be affected since the current through the pulse-widening circuit will then include a component due to grid current in the transmitting valve in the nonoperating means.

It is an object of the present invention, therefore, to provide a new and improved thermionic-valve system which avoids one or more of the above-mentioned disadvantages and limitations of prior such systems.

It is another object of the invention to provide a new and improved thermionic-valve system which includes therein an arrangement for selectively controlling the operation of each of a plurality of thermionic-valve systems which constitute said first-mentioned system.

In accordance with a particular form of the invention, a thermionic-valve system comprises a plurality of selectively operated thermionic-valve oscillatory systems each including at least one oscillator valve having an input circuit therefor and a self-bias means in each of the input circuits for developing a self-bias potential for the oscillator valve associated therewith when the oscillatory system including the aforesaid associated oscillator valve is selectively operated. The thermionic-valve system also includes a control system for applying, when any selected one of the oscillatory systems is operating, a control poten-

tial to the self-bias means of the oscillator in each nonoperating oscillatory system to prevent self-oscillation immediately upon selection of a nonoperating oscillatory system for operation. The system further includes means, responsive to the selection of the last-mentioned system for operation, for removing the control potential from the self-bias means of the oscillator valve thereof.

In order that the invention may be more readily understood it will now be described, by way of example and with reference to the accompanying drawings, with relation to its application to the control of two thermionic-valve responder systems in an aircraft for providing identification of the latter in conjunction with the pulsed exploring waves of two different types of radio-location apparatus. It is to be understood however that the invention is by no means limited to such an application or to the control of two thermionic-valve systems only.

In the accompanying drawings, Fig. 1 is a schematic representation of one form of responder means for receiving and retransmitting signal pulses transmitted from one e. g. ground, radio-location station; Fig. 2 represents schematically two responder means, embodying a control arrangement for receiving and retransmitting signal pulses transmitted from each of two types of ground radio-location station; Fig. 3 is a schematic diagram of a control arrangement adapted for use in connection with the two responder means represented in Fig. 2; and Fig. 4 is a schematic diagram of a control arrangement in accordance with an embodiment of the invention.

In the usual method of effecting the radio-location of aircraft, a pulsed exploring wave comprising a series of signal pulses, each pulse being formed by a short burst of radio-frequency energy, is transmitted from one or more ground stations. Such pulses, if incident upon an aircraft, are reflected therefrom and part of this reflected energy may be received by the ground station and applied to apparatus for giving an indication of the presence of the aircraft.

Such a reflected signal, however, does not give an indication of the nature of the aircraft. Thus in wartime it is impossible to state from such received signals whether the aircraft is of friendly or enemy origin.

In order to provide an indication of the nature of the aircraft, all aircraft of friendly origin may be fitted with a signal receiving and retransmitting means usually known as a responder. Such a responder may comprise the apparatus shown in the block diagram of Fig. 1 of the accompanying drawings. The signal pulses transmitted from the ground station are received by an aerial 40 and applied to a wave-signal selector or tuned circuit *a*, the tuning condenser of which sweeps through a band of frequencies including the carrier frequency of the pulsed exploring wave. When the circuit *a* is tuned to the carrier frequency of one particular ground station, each received pulse is amplified by a super-regenerative receiving circuit *b*, supplied with a quenching oscillation from an oscillator *c*. The output from stage *b* is applied to a detector circuit *d* and the rectified output therefrom is applied to a pulse-amplifier stage *e*. The amplified output is fed to a pulse-widening or shaping circuit *f*, which includes a capacitance the value of which may be varied automatically by suitable driving mechanism, and thence to the control grid of a trans-

mitting valve included in a modulated wave-signal transmitter *k*. The transmitting valve may be the same valve as that in the superregenerative stage *b*, or it may be a separate valve having the same tuned circuit *a* connected between its anode and control grid; that is to say, the tuned circuit *a* may be common to both the receiving valve and the transmitting valve. However, for the sake of simplicity, Fig. 1 of the drawings indicates a transmitter which is complete in itself. The arrangement of Fig. 1 does not embrace the present invention and all of its several components may have a construction and operation well understood by those skilled in the art, rendering a further detailed description thereof unnecessary.

By the provision of such apparatus a signal pulse received from a ground station, is translated in the usual way by superregenerator *a*, detected in detector *d*, amplified and shaped in units *e* and *f*, respectively, and applied as a modulating signal to transmitter *k*. Thus, a received pulse is retransmitted in amplified form and with considerably increased width, the increase in width being determined by the pulse-widening circuit *f*. This amplified and widened retransmitted pulse appears as such when rendered visible on the screen of a cathode-ray oscilloscope incorporated in the apparatus at the ground receiving station. Therefore, it is possible to distinguish between an aircraft fitted with the above-described responder means and an aircraft which is not so fitted by observing either the width or the height or both of the reply pulse signal received at the ground station.

Two classes of ground-station radio location are in general use, the carrier frequency of the pulses from each class being in a different frequency band. One class, which comprises early-warning stations, is employed for the purpose of giving a long-range indication of the approach of an aircraft. The other class is for short-range detection and, when provided in association with anti-aircraft batteries, is employed as a gun-laying station for the purpose of indicating the bearing and range of an aircraft. Since it is only necessary to know the bearing and range of an enemy aircraft just before the moment of firing, the effective area of this latter class of ground stations need only be small. Because the carrier frequencies of the signals from the two classes of ground station may be widely separated and, on account of their high value, it would appear necessary to provide an aircraft with two complete and independent sets of responder apparatus in order that appropriate identification signals may be returned to both classes of ground stations by a friendly aircraft. Where that is done, the frequency band of one responder includes only the carrier frequencies of the pulses transmitted from the early-warning stations and the frequency band of the other responder includes only the carrier frequencies of the pulses transmitted from the gun-laying stations. Such an arrangement has, however, several disadvantages. The apparatus is, of necessity, unduly large because only the supply unit is usually common to both responder circuits. Since the power supply has to be larger than that of a single responder, the supply unit itself is both heavier and more costly. A further technical difficulty arises because of mutual interference between the two aerial systems associated with the two responder circuits.

Since the aircraft is likely to be in an early-warning area for the greater part of its time,

it is sufficient in many installations if the responder apparatus of such aircraft is rendered responsive to early-warning stations for most of the time and if automatic switching means are provided to permit response to gun-laying stations for, say, two seconds in every six seconds, thus enabling the aircraft's presence to be made known should it enter a gun-laying area. It is essential, however, in order to avoid serious mistakes, that if the apparatus happens to be responsive to gun-laying stations upon entering a gun-laying area it is not then switched over so as to respond to signals from early-warning stations; or if it happens to be responsive to early-warning stations it will not, after the subsequent switching to respond to gun-laying stations, switch back again to respond to early-warning stations until the aircraft leaves the gun-laying area. That is to say, while the aircraft is within a gun-laying area, it should respond only to signals from gun-laying stations.

In Figs. 2 and 3 of the accompanying drawings two responder means of the type represented in Fig. 1 are embodied in an aircraft and associated with an improved control arrangement. The responders have certain of their components common to one another. Referring more particularly to Fig. 2, one responder means *x* is adapted to respond only to signal pulses transmitted from short range or gun-laying stations. The other responder means *y* is adapted to respond only to signal pulses transmitted from early-warning stations. Each circuit is similar to that of Fig. 1, the components peculiar to means *x* and *y* bearing the same reference letters as the corresponding components in Fig. 1 with either a prime or double-prime notation respectively. The quench-frequency oscillator *c* and the pulse amplifier *e* are common to both responders.

The output from the amplifier stage *e*, besides being taken to the pulse-widening or shaping circuits *f'* and *f''*, each of which includes a capacitance whose value may be varied automatically by a suitable driving mechanism, is arranged to be fed also to a diode rectifier *g* and then to a D. C. amplifier *h*. The amplified output from amplifier *h* is adapted to energize a control arrangement or switching system *i* arranged to cause operation of either superregenerative stage *b'* or superregenerative stage *b''*, and of either the driving mechanism included in pulse-widening circuit *f'* or the driving mechanism included in pulse-widening circuit *f''*.

The switching system *i*, see more particularly Fig. 3, comprises a change-over switching means, having one operating condition which permits the responders to operate singly in a predetermined cyclic order and having another operating condition which permits the substantially uninterrupted operation of only a specific responder, namely, that designated *x*. While this switching means may be provided by tube elements having off and on operating conditions, simplicity may be obtained from the use of a two-position, multi-sectional mechanical switch as illustrated. This switch is formed by five double-break single-pole switch sections 1, 2, 3, 4 and 5. One contact 1^a of the double-break single-pole switch element 1 is connected to the positive terminal of a high-tension supply, which supply is also connected to a spring blade 7 arranged to be cyclically actuated by a continuously rotating cam 8. The other contact 1^b of switch element 1 is connected to a contact 9 associated with spring blade 7 and also to the anode of the receiving valve

in the stage *b'* by way of the tuned circuit *a'*. The contact 2^a is connected to contact 10 associated with spring blade 7, and contact 2^b is joined to the anode of the receiving valve in stage *b''* by way of tuned circuit *a''*. Contact 3^a of double-break single-pole switch element 3 is connected to contact 11^a of another spring blade 11, which is arranged to be operated by a cam 8^a mounted rigidly on the same spindle as cam 8, contact 11^b coacting with contact 11^a being joined by way of a hold-on coil 12 to one terminal of a suitable, e. g. 12-volts, D. C. supply *E*. The other contact 3^b of switch element 3 is connected to the other terminal of the 12-volts supply *E*. Contact 4^a of double-break single-pole switch element 4 is joined directly to contact 5^a of double-break single-pole switch element 5 and is also connected to the first-mentioned terminal of the 12-volts supply *E*. Contact 5^b of switch element 5 is connected to the driving mechanism associated with pulse-widening circuit *f''* and contact 4^b is connected to the driving mechanism associated with the pulse-widening circuit *f'*. A contact 13, associated with spring blade 7, is connected by way of an energizing coil 14 to the anode of the valve forming the D. C. amplifier *h*. Contact 4^b and contact 5^b are joined together by way of the series connection of two 12-volt lamps 15, 16, the point common to the lamps being joined to contact 3^b and hence to the second-mentioned terminal of the 12 volts supply *E*.

Cam 8 is designed in such a manner that, during a complete period of its rotation, spring blade 7 makes contact with contact 18 for fourteen seconds and subsequently makes simultaneous contact with contacts 9 and 13 for two seconds. Cam 8^a is arranged to engage with a blister on spring blade 11 one second before spring blade 7 makes contact with contacts 9 and 13, the period of engagement being about one-half of a second. The cams are arranged to be driven continuously in an anti-clockwise direction.

It is arranged that a negative bias potential is applied to the control grid of the valve in the D. C. amplifier *h* of sufficient amount to prevent conduction. Its precise value is such that the D. C. potential across the diode rectifier *g* which would be developed as a result of the rectification of signal pulses received from early-warning stations and which is dependent upon the repetition frequency of the exploring wave pulses, is not sufficient to overcome this negative bias potential, whereas that due to rectification of signal pulses received from gun-laying stations, which pulses have a higher repetition frequency, is sufficient to overcome this bias potential.

In operation, when coils 14 and 12 are de-energized, the change-over switch is biased, e. g. by spring means 17, to a first position such that double-break single-pole switch sections 1, 3 and 4 are open and the double-break single-pole switch sections 2 and 5 are closed as shown. Assuming cam 8 to be in such an angular position as to cause spring blade 7 to make contact with contact 10, the high-tension supply is connected to the anode of the receiving valve in stage *b''* which is adapted to receive only signals transmitted from early-warning stations. Signals from these stations are received and the retransmitted signals are appropriately widened since a driving potential is applied to the driving mechanism associated with pulse-widening means *f''* from the 12 volts supply *E* by way of double-break single-pole switch element 5.

One second before spring blade 7 makes con-

tact with contacts 9 and 13, contact between 11^a and 11^b is broken by virtue of the engagement of cam 8^a with the blister on spring blade 11. No current is flowing through the hold-on coil 12 at this moment since double-break single-pole switch element 3 is open and hence the opening of contacts 11^a and 11^b has no effect upon the circuits. The opening of contacts 11^a and 11^b exists for about one-half of a second and after a further period of one-half of a second, spring blade 7 breaks contact with contact 10 and makes contact with contacts 9 and 13. The high-tension supply is now disconnected from the anode of receiving valve in stage b'' and is connected to the anode of receiving valve in stage b' which is adapted to receive only signals transmitted from gun-laying stations. The high-tension supply is also applied to the anode of the valve in the D. C. amplifier h by way of energizing coil 14.

If with spring blade 7 in this position the aircraft is outside a gun-laying area, no signals are received or accepted by selector a' from either gun-laying stations or early-warning stations. Further, the valve in the D. C. amplifier h is not able to conduct because of the cutoff bias applied to its control grid. This period exists for two seconds, being terminated when cam 8 releases spring blade 7 to again make contact with contact 10 and break contact with contacts 9 and 13. The high-tension supply is now reapplied to the anode of the receiving valve in stage b'', and hence signals from early-warning stations are again received and accepted by selector a'' for a period of fourteen seconds. After this fourteen-second period the high-tension supply is disconnected from receiving valve a'' and again connected to the receiving valve in stage b'. Thus, this first-described position of the change-over switch is one which permits the several responders to operate singly in a predetermined cyclic order. So long as the aircraft is outside a gun-laying area, it receives signal pulses from early-warning stations for fourteen seconds and then for two seconds it receives or accepts nothing.

If, however, the aircraft enters a gun-laying area during the period when the signals transmitted from early-warning stations are being received, the connection of the high-tension supply to the anode of the receiving valve in stage b' at the end of a fourteen-second period allows signals transmitted from a gun-laying station to be received. Also, the valve in the D. C. amplifier h now conducts because the high-tension supply is connected to it and because the repetition frequency of the pulses transmitted from a gun-laying station and translated by superregenerator b' is such as to cause the build-up of a potential across the diode rectifier g of sufficient amount to overcome the cutoff bias applied to the control grid of the valve on thermionic amplifier h.

Conduction of this valve causes energizing coil 14 to actuate and move the change-over switch to its second position in which the double-break single-pole switch elements 1, 3 and 4 are closed and switch elements 2 and 5 are opened. Closure of switch element 3 permits the 12-volts supply E to be applied to the hold-on coil 12 by way of spring blade 11 (the contacts 11^a and 11^b of which are now closed). This coil aids coil 14 in maintaining switches 1, 3 and 4 closed.

This operation is more or less instantaneous and exists for a period of two seconds. At the end of this period spring blade 7 makes contact

with contact 10 and breaks contact with contacts 9 and 13. Coil 14 is no longer energized because the high-tension supply is disconnected from the D. C. amplifier h, but, since switch 3 is closed and coil 12 is energized, the double-break single-pole switches 1, 3 and 4 remain closed. Signals from a gun-laying station continue to be received for a further period of thirteen seconds.

At this instant contacts 11^a and 11^b are broken, coil 12 is no longer energized since the 12-volts supply E is no longer applied to it and thus the change-over switch is returned from its second position back to its first position in which double-break single-pole switch elements 1, 3 and 4 are opened and double-break single-pole switch elements 2 and 5 are closed as shown in Fig. 3. Signals may now be received from early-warning stations. After one-half of a second spring blade 7 again makes contact with contacts 9 and 13 to initiate the normal two-second operation of the responder means x which is responsive to gun-laying stations. If during this period the aircraft is still in a gun-laying area, signals are received by the valve in stage b', the change-over switch is restored to its second position in the manner already described, and reception of signals from the gun-laying station is sustained for a further thirteen-second period as before.

If, however, the aircraft has left a gun-laying area, no signals are accepted during the period when spring blade 7 is in contact with contacts 9 and 13, and when, at the end of this period, these contacts are broken, the apparatus reverts to the first-mentioned operating condition for receiving signals from early-warning stations.

If the aircraft enters a gun-laying area while the change-over switch is in its second position and connecting the positive terminal of the high-tension supply to the anode of the receiving valve in stage b', signals from the gun-laying station are immediately received, and continue to be received until contacts 11^a and 11^b are subsequently broken, the mode of operation being exactly as described above.

It will thus be seen that while the aircraft is outside the area of a gun-laying station, the change-over switch is in its first operating position, permitting each of the thermionic-valve systems comprising the responder means x and y to operate singly in turn for the periods of two and fourteen seconds respectively assigned thereto by the cyclically operating switching means consisting of the cam-controlled spring blade 7 and contacts 9 and 10. With the change-over switch in this position, cam 8 and contacts 7 and 13 constitute automatic means for establishing at regular intervals a condition favorable to movement of the change-over switch from its first to its other operating position. The "regular intervals" referred to correspond to the operating periods cyclically assigned to responder x by cam 8 and contacts 7 and 9.

When however, the aircraft enters the area of a gun-laying station and it is accordingly desired that substantially uninterrupted operation of the specific system x responsive to such station should take place, the reception by the responder means x of gun-laying station signals during its two-second cyclic operative period is characterized by the conduction of the D. C. amplifier h. Coil 14 comprises electromagnetic actuating means, actuated by occurrence during that two-second period of a signal output from responder x which is present only when substantially uninterrupted operation of that responder is desired, for moving

the change-over switch. This effects movement of the change-over switch to its opposite or second operating position and its being held in this position by means of coil 12 until released by opening of contacts 11, 11a just before the system x is again due to be put into operation for its cyclic two-second period by the cyclically operated spring blade 7. If the aircraft is still within a gun-laying station area a repetition of events takes place whereby the system x is operated continuously except for a short interruption at the end of each cycle of the arrangement.

An indication as to whether an aircraft is in a gun-laying area or not is given to the pilot by means of lamps 15 and 16 which may be differently colored. When in a gun-laying area double-break single-pole switch element 4 is closed and the 12-volts supply E is applied to lamp 15. When outside a gun-laying area, switch element 4 is open and switch element 5 is closed, thereby connecting the 12-volts supply E to lamp 16.

In arrangements comprising two or more responder systems as above described certain difficulties may be found to arise during period of change-over from one thermionic-valve system to another, that is to say, when the high-tension supply is disconnected from one valve system and connected to another.

The first difficulty arises from the fact that the receiving valve and transmitting valve of each responder system are usually each provided with an automatic grid-biasing arrangement comprising a resistance in parallel with a condenser in their respective cathode leads. Consequently, when after one such system has been operating, the high-tension supply to it is disconnected due to movement of the spring blade 7, the condenser forming part of the grid-biasing means discharges and the potential of the cathode of the valve becomes nearly equal to earth potential. When the high-tension supply to this particular system is switched on again after a period during which the other responder system has been operating, the negative bias potential applied to the receiving valve and the transmitting valve in the first-mentioned system is small since their cathodes are nearly at earth potential, and it is usually so small as to allow self-oscillation to occur in each control-grid cathode circuit thereby causing unwanted transmission. This state of affairs continues until the cathode potentials rise to their normal operating values.

A second difficulty may arise because a D. C. connection is usually made to the control grid of the transmitting valve in the units k' and k'' in each responder from the cathode or anode of the valve in the amplifier stage e (Fig. 2) which is common to both means. When a signal pulse is received by an operating responder, the potential of the anode or cathode of the common amplifier valve in stage e rises. Hence not only does the potential of the control grid of the transmitting valve in the operating means rise positively, but so does the potential of the control grid of the transmitting valve in the nonoperating means. In the case of this latter valve, its anode potential is zero, its control-grid potential is positive and its cathode potential is nearly that of earth. Consequently, the control grid and cathode of this transmitting valve may operate as a diode valve, the control grid taking current. It will thus be seen that a transmitting valve in a non-operating means may thus add an extra load to the common amplifier valve, thereby reducing the driving power applied to the transmitting valve in

the operating responder system. This would cause a reduction in the amplitude of the pulse transmitted from the operating responder. Furthermore, the width of the pulse may be affected since the current through the pulse-widening circuit will then include a component due to grid current in the transmitting valve in the nonoperating responder system.

Fig. 4 shows an arrangement in accordance with the invention by which the above outlined difficulties may be avoided. In this figure, which shows two responder systems controlled by switching means similar to those of Figs. 2 and 3, the first responder system includes a receiver stage b' comprising a superregeneratively operated valve 20' having a parallel tuned resonant circuit a' connected between its anode and control grid with a tap on the inductance coil of such tuned circuit connected by way of contact 9 and spring blade 7 to the positive terminal of the high-tension supply source S. The cathode of the valve 20' is connected by way of an automatic grid-biasing arrangement comprising resistance 22' and parallel condenser 23' to the negative terminal of the supply source S.

The transmitting oscillator valve 21' of the first responder system is also arranged with the same tuned circuit a' connected between its anode and control grid while its cathode is likewise connected to the negative terminal of the high-tension supply S by way of a separate grid-biasing network of resistance 26' and parallel condenser 27'. This oscillator valve 21' is normally held inoperative by virtue of the value of negative grid bias applied thereto.

The second responder system is composed of substantially identical components and as these have similar reference numerals double primed, they will not be further described. The tap on the inductance coil a'' is connected in this instance by way of contact 10 and spring blade 7 to the positive terminal of the source S whereby each system may be operated alternately by appropriate movement of the spring blade 7 as already described in connection with Fig. 3.

The amplified received signal pulses in tuned circuit a' of Fig. 4 are fed by way of condenser 30' to a detector circuit, such as that of d' , Fig. 2, and the rectified output of the latter is then applied to the input circuit of an amplifier valve 29 constituting the equivalent of the stage e , Fig. 2. The circuit is arranged in such manner that a received signal pulse causes a rise in potential at either the anode, or preferably as shown, the cathode of the valve 29, and this rise is applied as a positive pulse to the control grid of the oscillator valve 21' by way of pulse-widening circuit f' , consisting of a parallel resistance-condenser network of suitable values. The application of this positive pulse to the control grid of the oscillator valve 21' causes the latter to burst into oscillation at the resonance frequency of the tuned circuit a' whereby a response signal is radiated in reply to the incoming pulse signal which initiated it. The value of the condenser of the pulse-widening circuit f' may be varied automatically by suitable driving means as already described in connection with Figs. 2 and 3 for the purpose of effecting a predetermined alteration in the width of the response signals to provide a coded reply signal in the manner more fully described in a copending application of Maurice K. Taylor and Frederic C. Williams, filed November 5, 1945, Serial No. 29,284/45, entitled improvements relating to Thermionic valve systems, and

assigned to the same assignee as the present application.

The amplified received signal pulses in tuned circuit a'' of the second responder system are similarly applied by way of a detector stage d'' , to the amplifier valve 29, the latter being made common to both systems for the purpose of economy in both cost, weight and power supply. The output potential of such valve, at either its anode or, as shown, its cathode is then applied by way of the pulse-widening circuit f'' to the control grid of the oscillator valve 21'' of this second responder system.

The manner of operation of the arrangement so far described has already been adequately dealt with and difficulty may arise in practice as outlined. For example, if the responder system comprising valves 20'' and 21'' is operating by virtue of spring blade 7 being in engagement with contact 10, the cathode potential of both valves 20' and 21' falls to that of the earthed negative high-tension supply terminal. While this is so, the positive pulses supplied from the amplifier valve 29 may raise the control grid of the valve 21' to such a potential that the control grid and cathode of this valve operate as a diode thus adding an extra and wasteful load upon the valve 29. When the spring blade 7 is operated to transfer high-tension supply to the valves 20' and 21' by way of contact 9, the zero grid bias existing initially on each valve may give rise to self-oscillating conditions until the condensers 23' and 27' become charged in the normal manner.

To obviate these difficulties, the cathode of valve 20' is connected by way of resistance 24' to the common high-tension supply lead to valves 20'' and 21'' while the cathode of valve 21' is likewise connected to the same high-tension supply lead by way of resistance 28'. Similarly the cathode of valves 20'' and 21'' are each connected by way of resistances 24'' and 28'' to the common high-tension supply lead to valves 20' and 21'.

In the operation of this, now modified, arrangement, when the spring blade 7 is in such a position as to connect the positive terminal of the high-tension supply S to the anodes of the first receiving and transmitting valves 20' and 21' the cathodes of the second receiving and transmitting valves 20'' and 21'' are maintained at a positive potential (with respect to their related control grids) because of the connections thereto from the high-tension supply to the first valve system. Also when the spring blade 7 is in such a position as to connect the positive terminal of the high-tension supply to the anodes of the second receiving and transmitting valves 20'' and 21'', the cathodes of the first receiving and transmitting valves 20' and 21' are likewise maintained at a positive potential (with respect to their related control grids).

By suitable choice of value for the resistances 24', 28' and 24'', 28'' the potentials of the cathodes of each receiving valve and transmitting valve in any nonoperating system may be arranged to be greater than that of their related control grids even during the period of application of a positive pulse from the amplifier valve 29 whereby such control grids and cathodes do not act as diode valves.

The arrangement may clearly be applied to three or more valve systems, each means being arranged to operate in turn. Connections are

made from the high-tension supply line of each system by way of resistances to the cathodes of the receiving and transmitting valves in each of the other systems.

Thus it will be seen that during its period of nonoperation, the cathode of each valve is held positive and that when the high-tension supply to such valve is switched on self-oscillation thereof is prevented.

Provided the switching-off of one thermionic-valve system and the switching-on of another system is effected substantially instantaneously, the arrangements so far described have been found satisfactory. If however, as frequently happens in practice, the switching means is such that there is a small time delay of the order of say one or two milliseconds between the switching-off of one system and the switching-on of another system a further difficulty may occur since, during this delay period the cathode potentials of the system which is about to become operative may fall from the values at which they have been maintained while nonoperative and self-oscillation may again occur.

To overcome this difficulty, the cathode of each of the valves is connected by way of a suitable capacitance to its own high-tension supply. Referring again to Fig. 4, a condenser 25' is connected between the cathode of valve 20' and its high-tension supply lead while a condenser 29' is connected between the cathode of valve 21' and the same high-tension supply lead. Similarly, condensers 25'' and 29'' are connected respectively between the cathodes of valves 20'' and 21'' and the high-tension supply lead thereto.

The operation with this modification is as already described with the following additional differences. During the period between switching off, say, the pair of valves 20'' and 21'' and switching on the other pair of valves 20' and 21' the potentials of the cathodes of the second pair of valves will fall from their positive values, the condenser of each grid-biasing means discharging to earth by way of its parallel resistance. Although the time period involved may be small, it may be sufficient to allow such a potential fall that self-oscillation will take place in the valves owing to an insufficient grid-bias potential at the moment when anode voltage is applied were it not for the condensers 25' and 29' which are connected between the high-tension supply line and the cathodes of the two valves. The capacity of these condensers is so chosen that the cathode potential of each valve rises with that of the anode, thereby charging momentarily the condenser of each grid-biasing means to an excessive potential. These potentials fall to the operating value as the condensers discharge to earth.

Similarly self-oscillation of the other pair of valves 20' and 21' at the instant of applying the high-tension supply thereto is prevented by the similarly connected condensers 25'' and 29''.

This feature of the invention may likewise be applied to three or more systems, each system being arranged to operate in turn, the cathode of each receiving valve and each transmitting valve being returned to its own high-tension supply line by way of a condenser.

Thus it will be seen that during the period of nonoperation, the cathode of a valve is held positive and then when the high-tension supply to a valve is switched on the cathode potential instantaneously rises with that of the anode. Thus self-oscillation of any valve is prevented. Although the invention has been described

with reference to responder systems as embodied in an aircraft for the purpose of indicating its nature to an interrogating ground station, it is also applicable to any other thermionic-valve systems which are arranged to operate singly in a predetermined order.

While there has been described what is at present considered to be the preferred embodiment of this invention, it will be obvious to those skilled in the art that various changes and modifications may be made therein without departing from the invention, and it is, therefore, aimed to cover all such changes and modifications as fall within the true spirit and scope of the invention.

What is claimed is:

1. A thermionic-valve system comprising: a plurality of selectively operated thermionic-valve oscillatory systems each including at least one oscillator valve having an input circuit therefor; a high-voltage energizing source for said oscillatory systems; self-bias means in each of said input circuits for developing a self-bias potential for the oscillator valve associated therewith when the oscillatory system including said associated oscillator valve is selectively operated; and a control system for temporarily applying from said source a control potential to the self-bias means of the oscillator valve in each nonoperating oscillatory system to prevent self-oscillation immediately upon selection of a nonoperating oscillatory system for operation.

2. A thermionic-valve system comprising: a plurality of selectively operated thermionic-valve oscillatory systems each including at least one oscillator valve having an input circuit therefor; self-bias means in each of said input circuits for developing a self-bias potential for the oscillator valve associated therewith when the oscillatory system including said associated oscillator valve is selectively operated; a control system for applying, when any selected one of said oscillatory systems is operating, a control potential to the self-bias means of the oscillator valve in each nonoperating oscillatory system to prevent self-oscillation immediately upon selection of a nonoperating oscillatory system for operation; and means, responsive to the selection of said last-mentioned system for operation, for removing said control potential from the self-bias means of the oscillator valve thereof.

3. A thermionic-valve system comprising: a plurality of selectively operated thermionic-valve oscillatory systems each including at least one oscillator valve having an input circuit therefor; self-bias means including a cathode resistor in each of said input circuits for developing a self-bias potential for the oscillator valve associated therewith when the oscillatory system including said associated oscillator valve is selectively operated; a control system for applying, when any selected one of said oscillatory systems is operating, a control potential to the cathode resistor of the oscillator valve in each nonoperating oscillatory system to prevent self-oscillation immediately upon selection of a nonoperating oscillatory system for operation; and means, responsive to the selection of said last-mentioned system for operation, for removing said control potential from the cathode resistor of the oscillator valve thereof.

4. A thermionic-valve system comprising: a plurality of selectively operated thermionic-valve oscillatory systems each including at least one oscillator valve having a cathode and including

an input circuit coupled thereto; self-bias means including a cathode resistor in each of said input circuits for developing a positive self-bias potential at the cathode of the oscillator valve associated therewith when the oscillatory system including said associated oscillator valve is selectively operated; a control system for applying, when any selected one of said oscillatory systems is operating, a positive control potential to the cathode of the oscillator valve in each nonoperating oscillatory system to prevent self-oscillation immediately upon selection of a nonoperating oscillatory system for operation; and means, responsive to the selection of said last-mentioned system for operation, for removing said positive control potential from the cathode of the oscillator valve thereof.

5. A thermionic-valve system comprising: a plurality of selectively operated thermionic-valve oscillatory systems each including at least one oscillator valve having an input circuit therefor; a source of high-voltage energizing potential for said oscillator valves; self-bias means in each of said input circuits for developing a self-bias potential for the oscillator valve associated therewith when the oscillatory system including said associated oscillator valve is selectively operated by the application of said energizing potential thereto; a control system for deriving from any selected one of said oscillatory systems during operation thereof a control potential and for applying said control potential to the self-bias means of the oscillator valve in each nonoperating oscillatory system to prevent self-oscillation immediately upon selection of a nonoperating oscillatory system for operation; and means, responsive to the selection of said last-mentioned system for operation, for removing said control potential from the self-bias means of the oscillator valve thereof.

6. A thermionic-valve system comprising: a plurality of selectively operated thermionic-valve oscillatory systems each including at least one oscillator valve having a cathode and including an input circuit coupled thereto; a source of high-voltage energizing potential for said oscillator valves; self-bias means including a cathode resistor in each of said input circuits for developing a positive self-bias potential at the cathode of the oscillator valve associated therewith when the oscillatory system including said associated oscillator valve is selectively operated by the application of said energizing potential thereto; a control system including said resistors individual to each of said oscillator valves for deriving from any selected one of said oscillatory systems during operation thereof a positive control potential and for applying said derived potential to the cathode of the oscillator valve in each nonoperating oscillatory system to prevent self-oscillation immediately upon selection of a nonoperating oscillatory system for operation; and means, responsive to the selection of said last-mentioned system for operation, for removing said positive control potential from the cathode of the oscillator valve thereof.

7. A thermionic-valve system in accordance with claim 6, in which each of said plurality of thermionic-valve oscillatory systems includes a plurality of oscillator valves.

8. A thermionic-valve system comprising: a plurality of selectively operated thermionic-valve oscillatory systems each including at least one oscillator valve having a cathode resistor and including an input circuit coupled thereto; a source

15

of high-voltage energizing potential for said oscillator valves; self-bias means including a cathode resistor in each of said input circuits for developing a positive self-bias potential at the cathode of the oscillator valve associated therewith when the oscillatory system including said associated oscillator valve is selectively operated by the application of said energizing potential thereto; a control system including said resistors individual to each of said oscillator valves for deriving from any selected one of said oscillatory systems during operation thereof a first positive control potential and for applying said derived potential to the cathode of the oscillator valve in each nonoperating oscillatory system to prevent self-oscillation immediately upon selection of a nonoperating oscillatory system for operation; means, responsive to the selection of said last-mentioned system for operation, for removing said positive control potential from the cathode of the oscillator valve thereof; and means including individual condensers for each of said oscillator valves and responsive to said selection of said last-mentioned oscillatory system for applying to the cathode resistor of each oscillator valve thereof during an immediately subsequent relatively short time interval a second positive control potential effective further to prevent said self-oscillation during said interval.

9. A thermionic-valve system in accordance with claim 8, in which each of said plurality of thermionic-valve oscillatory systems includes a plurality of oscillator valves.

10. A thermionic-valve system comprising: a plurality of selectively operated thermionic-valve oscillatory systems each including at least one oscillator valve having an input circuit therefor; a high-voltage energizing source for said oscillatory systems; self-bias means in each of said input circuits for developing a self-bias potential for the oscillator valve associated therewith when the oscillatory system including said associated oscillator valve is selectively operated; and a control system responsive to the selection of any nonoperating oscillatory system for applying from said source to the self-bias means of each oscillator valve thereof during an immediately subsequent relatively short time interval a control potential effective to prevent self-oscillation of said last-mentioned system during said interval.

11. A thermionic-valve system comprising: a plurality of selectively operated thermionic-valve oscillatory systems each including at least one os-

16

cillator valve having an input circuit therefor; self-bias means in each of said input circuits for developing a self-bias potential for the oscillator valve associated therewith when the oscillatory system including said associated oscillator valve is selectively operated; a control system for applying, when any selected one of said oscillatory systems is operating, a control potential to the self-bias means of the oscillator valve in each nonoperating oscillatory system to prevent self-oscillation immediately upon selection of a nonoperating oscillatory system for operation; and a control arrangement, for selectively operating each of said plurality of oscillatory systems singly in predetermined cyclic order, including switching means responsive to the selection of a nonoperating oscillatory system for operation for removing said control potential from the self-bias means of the oscillator valve thereof.

20 12. A thermionic-valve system comprising: a plurality of selectively operated thermionic-valve oscillatory systems each including at least one oscillator valve having an input circuit therefor; self-bias means in each of said input circuits for developing a self-bias potential for the oscillator valve associated therewith when the oscillatory system including said associated oscillator valve is selectively operated; a control system for applying, when any selected one of said oscillatory systems is operating, a control potential to the self-bias means of the oscillator valve in each nonoperating oscillatory system to prevent self-oscillation immediately upon selection of a nonoperating oscillatory system for operation; and a control arrangement, for permitting each of said plurality of oscillatory systems to operate singly in predetermined cyclic order or for permitting the substantially uninterrupted operation of only a specific one of said oscillatory systems, 35 including switching means responsive to the selection of a nonoperating oscillatory system for operation for removing said control potential from the self-bias means of the oscillator valve thereof.
